UNITED STATES PATENT OFFICE.

JOHN W. BRAGGER, OF WATERTOWN, NEW YORK, ASSIGNOR TO J. B. WISE, INC., OF WATERTOWN, NEW YORK, A CORPORATION OF NEW YORK.

DESIGN FOR A SANITARY TRAP.

46,197.

Specification for Design.

Patented Aug. 4, 1914.

Application filed December 6, 1913. Serial No. 805,166. Term of patent 14 years.

To all whom it may concern:

Be it known that I, JOHN W. BRAGGER, a citizen of the United States, residing at Watertown, in the county of Jefferson and State of New York, have invented a new, original, and ornamental Design for a Sanitary Trap, of which the following is a specification, reference being had to the accompanying drawing, forming part thereof.

Figures 1 and 2 are elevational views of a sanitary trap showing my new design.

I claim:

The ornamental design for a sanitary trap, as shown.

JOHN W. BRAGGER. [L. S.]
